UNITED STATES PATENT OFFICE.

EDMUND DONALD ROBERTS, JR., OF DETROIT, MICHIGAN.

PROCESS OF MAKING A DESIGN PAINTING.

No. 855,812.

Specification of Letters Patent.

Patented June 4, 1907.

Application filed June 7, 1906. Serial No. 320,630.

To all whom it may concern:

Be it known that I, EDMUND DONALD ROBERTS, Jr., a citizen of the United States, residing at Detroit, in the county of Wayne, 5 State of Michigan, have invented certain new and useful Improvements in Processes of Making a Design Painting; and I do declare the following to be a full, clear, and exact description of the invention, such as will enable 10 others skilled in the art to which it appertains to make and use the same.

This invention relates to a process of making a design or sketch in black and white, or in colors, for lithographic or other reproduction.

The object of the invention is to produce a painted design or sketch for reproduction in black and white, or in colors, by a process which requires but a comparatively short 20 time, and enables a painting of superior merit to be produced at a comparatively small cost, at the same time preserving all of the fine detail and correctness of drawing incident to photographing from life, or to photographic reproduction of any subject.

The above object is attained by my process which is illustrated in the accompanying drawing and described as follows:—

A figure is photographed from life, or a subject is photographed from a painting or drawing and a photographic print *a* made from the developed negative upon platinum or other sensitized material that will print properly; the photographic print is then 35 mounted upon a backing *b* and the entire surface of the paper or material upon which the print is made, excepting that portion which is to be treated by water colors is sized with a suitable sizing *c*, such as glue or white shellac. By employing said sizing the oil paint 40 of which the back ground is made, is prevented striking through or in any manner affecting the paper or the photographic print. The back ground is then painted in oil *d* over 45 the sized surface to produce a landscape, wooded scene, marine view, or other effect desired, and the photographic print is colored, in whole or in part, by water colors *e*. Because of the fact that water colors are transparent, the detail of the photographic print 50 is not destroyed, nor covered up in their use,

enabling the attainment of a naturalness in form and feature, and a correctness as to drapery and the distribution of lights and shades unattainable by the use of oil colors, 55 for the reason that oil colors, being opaque, would, to a great extent, cover up the photographic detail and destroy the naturalness of posture and expression, which the photograph presents, besides there is an additional 60 advantage in the use of water colors for the reason that they may be much more quickly and satisfactorily applied to produce the color effect desired upon the photographic subject. It will now be evident, that, by employing water colors on a photographic print wherein it is desired to preserve the photographic detail, and by painting in oil the other parts of the sketch or design not treated by the water colors, a painted sketch for 65 reproduction in black and white, or in colors, 70 may be produced of a superior character at a greatly reduced cost.

Having thus fully set forth my invention, what I claim as new and desire to secure by 75 Letters Patent is:—

1. The method of producing a sketch or painting which consists in photographing a subject, printing from the photograph upon suitable material, mounting the print, painting in oil the surface of the sketch not occupied by the subject, and painting the photographic subject in transparent colors.

2. The process of producing a sketch or drawing for reproduction which consists in 85 photographing a subject, printing from the photograph upon sensitized material, sizing the surface of said material around said subject, painting in oil upon the sized surface, and painting the photographic subject in 90 water colors.

3. A painting consisting of a photographed subject, colored in whole or in part, by the application of transparent pigment, and a back ground surrounding said subject 95 painted in oil.

In testimony whereof, I sign this specification in the presence of two witnesses.

EDMUND DONALD ROBERTS, JR.
